UNITED STATES PATENT OFFICE.

GEORGE BENTLEY BERGEN, OF CHICAGO, ILLINOIS.

PERMUTATION LOCKING-RING.

1,388,691.

Specification of Letters Patent. Patented Aug. 23, 1921.

Application filed February 6, 1919. Serial No. 275,303.

To all whom it may concern:

Be it known that I, GEORGE B. BERGEN, a citizen of the United States, and resident of Chicago, in the county of Cook and State 5 of Illinois, have invented certain new and useful Improvements in a Permutation Locking-Ring, of which the following is a specification.

My invention relates to locking devices, 10 particularly to a novel permutation ring lock.

One of the principal objects of this invention is to provide a locking device in the form of a ring or annulus, a section of the 15 ring being movable in line with a portion of the body of the ring in order to provide an opening in the ring. The movable part is adapted to be held in locking position by means of a plurality of cylinders held in 20 rotative position within the body of the ring member, these cylinders being so constructed and arranged as to be adapted for easy rotation from the exterior of the ring. Numerals disposed on the peripheries of the 25 cylinders are so arranged as to be viewed through sight apertures provided in the ring casing and in such manner that the combination will be set in order to effect the unlocking result.

30 The mounting of the cylinders which correspond to the tumblers of an ordinary permutation lock constitutes one of the important features of the invention. These are so arranged that they are concentric with 35 the locking bolt and as it is not essential that any material portions thereof project beyond the periphery of the ring casing, the locking device is to all practical purposes when locked, a complete symmetrical annulus having no projecting parts. That the device has no projections is of the utmost importance for when the device is made of a resistant material such as hardened 40 steel, it is extremely difficult to break it. 45 This is so because there are no projecting portions of the ring which may serve as a fulcrum for an instrument used for breaking the lock.

The lock may be employed for a multitude 50 of purposes which need not be enumerated. It may assume other forms than that of an annulus.

The invention will be more readily understood by reference to the accompanying 55 drawing, wherein,

Figure 1 is an elevation of a ring pad-

lock constructed in accordance with my invention;

Fig. 2 is a sectional view therethrough showing the bolt in locked position; 60

Figs. 3 and 4 are sectional views on the lines 3—3 4—4 respectively of Fig. 2;

Fig. 5 is a view similar to Fig. 2 showing the bolt in unlocked position;

Fig. 6 is an edge view of the device, and, 65

Fig. 7 is an enlarged elevation of one of the locking cylinders or sleeves.

In the drawings it will be seen that in the preferred embodiment of the invention the padlock is composed of a tubular ring 10, 70 which is incomplete, the open space being adapted to be closed by the arcuate bolt 11. This bolt is provided near one end with a peripheral flange 12, which serves as a limit stop in the two extreme positions of the 75 bolt, as shown in Figs. 2 and 5. Near the other extremity of the bolt I provide three lugs or projections 13, located in parallelism. These lugs are adapted to serve as the locking devices and to coöperate with the so-called tumblers or sleeves 14. One of these devices is shown in Fig. 7, by which it will be seen that it comprises a cylindrical portion which is substantially the size of the space within the tubular ring 10, this portion 80 serving to guide and support the tumbler in its rotation. The tumbler has a knurled or milled flange 15, and is provided with an end wall 16, having an aperture 17, of substantially the size of the bolt 11. 90 At one point in the aperture I provide a notch 18, best shown in Fig. 4, of a size substantially equal to the projections or lugs 13, on the bolt. The periphery of the cylindrical portion of the tumbler has numerals 19, disposed thereon, these numerals being adapted to be exposed through small sight apertures 20, formed in the ring 10, 95 at the proper point.

It will be noted by reference to Figs. 4 100 and 6, that the ring 10, is flattened somewhat at the point of engagement with the tumblers 14, the flat sides 21, being brought into engagement with the cylindrical portions of the tumblers. The remainder of 105 the ring portion at the point of engagement with the tumblers is flared or enlarged somewhat to overlie the milled flange 15, on the tumblers. Thus the flange may readily be engaged by the fingers at the sides but is 110 retained and guided by the enlarged portion.

In assembling the device the ring is formed over the tumblers, being seamed or welded on the line 22. It will be understood, of course, that the notches 18, in the tumblers 5 will be located at different points with relation to the numbers on the periphery and therefore that different combinations of numbers will be required in order to bring the tumblers in such positions that the 10 notches will be in line to permit the bolt to be retracted.

The form and arrangement of the parts are not essential and various modifications 15 may be made therein. Means other than the arcuate bolt may be employed in differently shaped structures and the devices for opening the ring may be changed. The essential feature of the lock is considered to be the simple arrangement of the tumblers and 20 the resultant economy in manufacturing cost.

It will be apparent that the locking tumblers may be disposed in the opposite end of the ring casing if desired, in which case 25 the projections 13, on the bolt will be located on the opposite end of the bolt. This will provide a somewhat stronger construction as when locked the two ends of the casing will be fixedly united.

I claim:

1. In a locking device, the combination of a hollow, incomplete annulus, an arcuate bolt 30 movable in said annulus and adapted to complete the same, a plurality of locking cylinders mounted within the annulus and adapted 35 to surround the bolt, each of said cylinders being provided with a notch, and projections on said bolt adapted to coöperate with the notches when the cylinders are 40 properly disposed, substantially as described.

2. In a device of the class described, the combination of a tubular casing, a bolt adapted to slide in said casing, a plurality of cylinders mounted within the tubular casing 45 in end to end relation and fixedly held therein against longitudinal movement, said cylinders being adapted to surround the bolt, and being provided with notches and with exteriorly displayed numerals correlated 50 with the notches, and projections on the bolt adapted to coöperate with said notches, substantially as described.

3. In a device of the class described, the combination of a tubular, incomplete annulus, a bolt mounted with capacity for telescoping in said annulus, said bolt being provided with a plurality of alined projections, 55 a plurality of cylindrical tumblers concen-

trically mounted within the tubular annulus and adapted to receive the bolt, said cylinders being flanged, a portion of the flanges projecting outside of the limits of the annulus whereby to provide a finger grip for rotating the cylinders, said cylinders being provided with notches adapted to coöperate 60 with the projections on the bolt, substantially as described.

4. In a locking device, the combination of an incomplete, annular, tubular casing, a bolt adapted to reciprocate within the casing, a plurality of cylindrical tumblers mounted within the casing, a bolt adapted to project through the tumblers, said tumblers having a cylindrical portion and a flange portion, 70 said casing being pressed to provide a recess for a portion of the flange of each cylinder and notched to permit a portion of the flange to project outside of the casing, substantially as described.

5. In a locking device, the combination of a tubular casing, a bolt adapted to telescope 75 therein, a plurality of cylindrical tumblers mounted within said tubular casing, a flange on each of said tumblers, said flanges projecting outside of the limits of said tubular 80 casing for a portion of their extent, said cylinders being provided with an interior notch, projections on said bolt, adapted to coöperate with the notches in said cylinders, 85 each of said tumblers having numerals displayed on the periphery thereof, and said casing being provided with openings through which said numerals may be viewed, substantially as described.

6. In a locking ring, the combination of an incomplete tubular annulus, an arcuate bolt adapted to telescope within said annulus and to close the opening in the annulus, 90 said bolt being provided with projections, a plurality of hollow, cylindrical tumblers adapted to receive said arcuate bolt, said tumblers being interiorly notched to coöperate with the projections on the bolt, said tumblers being provided with flanges adapted to furnish a finger grip for rotating the tumblers, the tumblers being mounted within the tubular annulus, the annulus being flattened and notched to permit of the projection of a portion of a flange of each tumbler outside of the limits of the tubular annulus, substantially as described.

Signed at Chicago, Ill., this 1st day of February, 1919.

GEORGE BENTLEY BERGEN.
